UNITED STATES PATENT OFFICE.

CHARLES S. CAMPBELL, OF NEW HAVEN, AND WILLIAM H. DAY, OF EAST HAVEN, CONNECTICUT, ASSIGNEES TO INDEX VISIBLE, INC., OF NEW HAVEN, CONNECTICUT, A CORPORATION OF NEW YORK.

INDEX OR FILE.

1,421,670.

Specification of Letters Patent. Patented July 4, 1922.

Application filed November 30, 1920. Serial No. 427,302.

To all whom it may concern:

Be it known that we, CHARLES S. CAMPBELL and WILLIAM H. DAY, citizens of the United States, residing, respectively, in New Haven and in East Haven, in the State of Connecticut, have invented certain new and useful Improvements in Indexes or Files, of which the following is a specification; reference being had to the accompanying drawings, forming a part hereof.

This invention relates to indexes or files of the character of those shown, for example, in Letters Patent of the United States No. 1,048,050, dated December 24, 1912, in which each base card or index card is formed with die cut portions which serve both to secure the card detachably to a support and to maintain the several cards of a series in overlapped relation so that the margin of each card of the series shall be visible. The present invention has been developed in the effort to meet the requirements of certain particular uses of such indexes or files. For such uses it is sometimes necessary to provide for the association with each index card or base card of a separate and easily removable record card or slip, on which is inscribed information related to the indexed subject, but changed or transferred from time to time. It has been sought heretofore to meet the requirements of such use by providing each index card or base card with a pocket, sometimes of transparent material, for the reception of the removable index card or slip, but this generally involves the provision of special index cards or slips adapted for such use, whereas the user might prefer to have his own index cards or slips, or index cards or slips which can be secured readily in the market. It is the object of this invention to provide an index or file having a series of overlapping index cards or base cards, adapted to support, in association therewith, removable record cards or slips without the necessity of providing pockets on the index or base cards to receive the record cards or slips and without imposing specific requirements as to the character of such record cards or slips. A further purpose is to provide such means for supporting such index or base cards and record cards or slips that the record cards or slips can be removed and replaced readily and their accidental dis-

placement prevented, notwithstanding the absence of pockets on the base cards, and that the base cards themselves shall be protected against injury as they are pulled forward to permit the removal and replacement of index cards. In the construction shown in the Letters Patent above mentioned the die cut portions of each card are directed inwardly to engage the outwardly directed edges or flanges of the narrow supporting strip, but in the present instance, in order that the base or index card shall be engaged with the support nearer its lateral edges, and thereby better serve its purpose in such use as that referred to, the die cut portions are directed outwardly to engage inwardly directed flanges of the support or leaf, and such support or leaf is provided at each side with a guard flange which prevents the accidental displacement laterally of the record cards and at the same time restrains somewhat the forward movement of the index or base cards when record cards are being inserted or removed, although such guard flanges serve no purpose in holding the index cards to the support or leaf. The invention will be more fully explained hereinafter with reference to the accompanying drawings in which it is illustrated as embodied in a convenient and practical structure, and in which—

Figure 1 is a view in elevation showing a hinged support or leaf with several index and record cards in place thereon.

Figure 2 is a detail view in section on the plane indicated by the broken line 2—2 of Figure 1 and on a larger scale.

Figure 3 is a detail view in horizontal section on the plane indicated by the broken line 3—3 of Figure 1.

Figure 4 is a detail view in elevation and partly broken out to show the relations of the index and record cards, on a scale larger than that of Figure 1.

Figure 5 is a view similar to Figure 3, but showing a slightly different construction.

Each index or base card *a*, has die cut portions or ears *a'* united to the body of the card along a horizontal line separated from the lower edge of the card by a space substantially equal to the space by which the upper edge of each card is to rise above the upper edge of the preceding card, if the

cards are arranged in upstanding fashion, as indicated in the drawing, or by which the edge of each card is to extend below the edge of the preceding card, if the cards 5 are arranged in down-hanging fashion as might be represented by turning the drawing upside down, and are curved or otherwise formed so as to present a free end toward the corresponding lateral edge of the 10 card. In the construction shown in the Letters Patent above mentioned the die cut portions or ears are directed inwardly toward each other, for the purpose of engaging the outwardly turned flanges of the 15 narrow supporting strip, but in the present instance, as shown, these die cut portions or ears are turned outwardly partly so as to place the ears nearer the lateral edges of the card and partly so as to facilitate 20 the manipulation of the cards in applying them to and in removing them from the leaf or support to be described. It will be understood that when the cards of a series 25 are assembled they are maintained in the desired overlapped relation, with the index margin of each card visible beyond the next card, by the fact that the edge, upper or lower as the case may be, of one card rests against the die cut portions or ears 30 of the next card at or near the line of juncture of the die cut portions or ears with the body of the card. For the particular use referred to, namely, in connection with removable record cards, the upper or free 35 edge of each index or base card a , has a shallow notch in the middle, as at a^2 , to facilitate the manipulation of the corresponding record card. Any desired record 40 card b can be used in combination with the index or base cards described, provided its width in a vertical line is less than the width, in a vertical line, of the index or base card, but in order to realize fully the advantages of the improved construction, 45 each record card b has a width, in a vertical direction, not only less than the width in a vertical direction of the index or base card, but greater, in a vertical direction than the width of the index or base card 50 from its free edge to the line indicated by the broken line at a^3 in Figures 1 and 4 on which the die cut portions or ears a' are joined to the body of the corresponding card a , so that a margin b' of the record 55 card shall be visible above, (in the case of upstanding cards) the edge of the index or base card next in front of it, and so that a margin a^4 of each index or base card shall be visible above the edge of the record card 60 next in front of it. The same identifying or indexing mark, such as a room number, in a hotel index, can thus be placed upon the margin of each index card and upon the margin of the corresponding record card, 65 so that both shall be visible to the user and

the proper assembling of the cards assured. The absence of any record card, or its presence in reverse position would then indicate, for example, that the particular room is vacant. For convenience in manipulation the record cards have less width in a horizontal direction than the index or base cards, as indicated in Figures 1 and 4.

The support or leaf c upon which the cards are mounted, may be formed of any suitable 70 material and in any convenient manner. As shown in Figures 1, 2, 3 and 4 the support or leaf consists of a thin sheet c' of metal, which may be stiffened by a wire at its edge, as shown as c^2 , and has secured thereto near 75 each lateral edge, as by rivets c^3 , and on each face, if desired, a strip c^4 , the inner edges of which are free, as at c^5 , to form inwardly directed flanges for co-operation with the outwardly directed tongues or die cut portions 80 a' of each index card. The outer marginal portion c^6 of each strip c^4 is turned outwardly, away from the sheet c' , and then preferably parallel therewith for a short distance to form a guard flange, first to prevent the record cards, (which are not held in pockets) from being slipped out at one side or the other, and, second, to restrain the index or base cards from being pulled too 85 forward when record cards are being removed or replaced. The height of the flange, that is the distance between the body of the strip c^4 and the lip c^5 , is substantial, so as to permit each index card to be pulled out far enough for easy manipulation of the record 90 card and also to permit the convenient manipulation of the index or base cards in placing them on or removing them from the support or leaf, and the flanges therefore do not serve to retain the index cards in place 95 or in assembled relation. The marginal portions of each strip c^4 may also be turned back upon themselves, as at c^6 , to stiffen the structure and prevent the presentation of a raw edge.

It will be obvious that the support or leaf might be formed in various ways as shown in Figure 5, for example, the main or central portion c^{11} might be formed itself with the inturned flanges c^{12} and the strips c^{13} , provided with the guide flanges c^{14} , formed as before, might be riveted, as at c^{15} against the rear face of the body c^{11} .

In the use of the improved indexes or file, the index or base cards a are first applied to 120 the support or leaf c , being slightly buckled so as to permit their lateral edges to be slipped under the guards c^6 and the die cut portions or ears a' to be engaged with the flanges c^5 . Then they are pushed together 125 until they assume the desired overlapping relation. Finally each record card, as prepared, is inserted in its proper place, the index or base card in front of its position being pulled forward slightly to permit the 130

record card to be slipped readily into place. Any record card can be withdrawn readily at any time either to receive additional matter or to be replaced by another card.

5 It will be obvious that various changes in details can be made to suit different conditions of use and that the invention is not limited to the precise construction shown and described herein, except as pointed out
10 in the claims.

We claim as our invention:

1. In an index or file, a sheet metal support comprising a main body portion and lateral strips secured thereon and having
15 their edge portions turned forward and inward to form guard flanges, inwardly directed retaining flanges being formed on said support.

2. In an index or file the combination of a
20 support having retaining flanges, index cards having die cut portions or ears to engage said flanges and to maintain the cards in overlapped relation, and record cards of less width in a vertical direction than the
25 index cards and bearing at one edge against the die cut portions or ears of the corresponding index cards.

3. In an index or file the combination of a support having retaining flanges and having at its edges guard flanges, index cards 30 having die cut portions to engage the retaining flanges, and record cards of less width in vertical direction than the index cards inserted between the index cards.

4. In an index or file the combination of a 35 support having retaining flanges within its edges and having forwardly and inwardly turned guard flanges at its edges, index cards formed with die cut portions or ears to engage the retaining flanges and having their 40 lateral edges covered by the guard flanges and record cards inserted between the index cards.

5. In an index or file the combination of a 45 support having retaining flanges within its edges and having guard flanges at its edges and index cards having die cut portions or ears to engage the retaining flanges and having their lateral edges guarded by the
50 guard flanges.

This specification signed this 27th day of November, A. D. 1920.

CHARLES S. CAMPBELL.
WILLIAM H. DAY.
